CLAIM

The ornamental design for a game pad, as shown and described.

DESCRIPTION

FIG. 1 is a top left front perspective view of a game pad showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top right rear perspective view thereof; and, FIG. 9 is a top left rear perspective view, in which a head-mounted display device in dot-dash broken lines is provided to illustrate an example environment.

The short dash-dot broken line in the figures represents unclaimed portions of the game pad and the dot-dash broken line showing of a head-mounted display device in FIG. 9 is for the purpose of illustrating environmental structure; the broken lines form no part of the claimed design.
